PALM HELD HAIR STYLING TOOL

Annie R. Thomas, 700 E. Emily, Longview, Tex. 75601

Substituted for abandoned design applications Ser. No. 2,718, June 20, 1966, and Ser. No. 10,653, Feb. 20, 1968. This application June 2, 1970, Ser. No. 23,261

Term of patent 14 years

Int. Cl. D28—03

U.S. Cl. D86—8

FIG. 1

FIG. 3

FIG. 1 is a front elevational view of a palm held hair styling tool showing my new design, the side opposite being identical thereto;

FIG. 2 is a cross sectional view thereof taken on the line 2—2 of FIG. 1; and

FIG. 3 is a front perspective view of the design.
I claim:

The ornamental design for a palm held hair styling tool, substantially as shown and described.
